ABSTRACT

A pipe organ ensemble effect results when two similar pipes, slightly out-of-tune with respect to each other, are sounded together upon selection of a single instrument key. Herein, apparatus is disclosed for producing an ensemble effect in a computor organ of the type wherein musical notes are generated by computing the amplitudes at successive sample points of a musical waveshape and converting the amplitudes to sounds as the computations are carried out in real time. Each amplitude is computed during a regular time interval t_x by separately calculating a set of "combined" Fourier components which are accumulated to obtain the sample point amplitude. Each nth order combined Fourier component is evaluated by summing a pair of sinusoid values associated respectively with the nominal tone and the frequency offset, "out-of-tune" tone. The sum is multiplied by a harmonic coefficient to establish the relative amplitude of that combined Fourier component.

PRODUCTION OF ENSEMBLE IN A COMPUTER ORGAN

BACKGROUND OF THE INVENTION

1. Field of the Invention

The present invention relates to the production of ensemble in a computer organ.

2. Related Applications

This invention is related to the inventor's copending U.S. patent applications Ser. No. 225,883 filed on Feb. 14, 1972 entitled COMPUTER ORGAN now U.S. Pat. No. 3,809,786, Ser. No. 298,365 filed on Oct. 17, 1972 entitled COMPUTER ORGAN USING PARALLEL PROCESSING now U.S. Pat. No. 3,809,788, Ser. No. 321,231 filed on Jan. 5, 1973 entitled PRODUCTION OF CELESTE IN A COMPUTER ORGAN now U.S. Pat. No. 3,809,792, and Ser. No. 374,680 filed on June 28, 1973 entitled ANHARMONIC OVERTONE GENERATION IN A COMPUTER ORGAN.

3. Description of the Prior Art

An ensemble effect is produced in a pipe organ by using two or more ranks of pipes, one of which is tuned to the nominally correct 8-foot frequency while another is slightly out-of-tune. When a single keyboard switch is depressed, both the in-tune and out-of-tune pipes are sounded. The resultant beat frequencies are most pleasant to the listener. An ensemble effect using two sets of pipes also is known as "tone doubling." More complex effects are achieved using three or four sets of pipes to produce "trio" or "quartet" ensemble.

In conventional electronic organs an ensemble effect is obtained by using separate sets of oscillators offset in frequency with respect to the nominal tone generators. When mixed electronically or acoustically, the combined generator outputs produce a reasonable facsimile of ensemble. Alternatively, two separate and complete electronic organ systems, detuned with respect to each other and used to drive different speakers, may be used to produce ensemble. Such approaches are expensive, and virtually rule out trio or quartet ensemble as beyond acceptable cost limits.

An object of the present invention is to implement ensemble in a computer organ. The system add-on is inexpensive and readily facilitates doubling, trio or quartet ensemble effects.

SUMMARY OF THE INVENTION

In a COMPUTER ORGAN of the type described in the above mentioned patent application Ser. No. 225,883, now U.S. Pat. No. 3,809,786, musical notes are produced by computing in real time the amplitudes $X_o(qR)$ at successive sample points qR of a musical waveshape, and converting these amplitudes to notes as the computations are carried out. In accordance with the present invention, each sample point amplitude is computed during a regular time interval t_s according to the relationship

$$X_o(qR) = \sum_{n=1}^W C_n \left[\sin \frac{\pi}{W} nqR + \sin \frac{\pi}{W} (nqR + \frac{nqR}{\kappa}) \right] \quad (Eq. 1)$$

where q is an integer incremented each time interval t_s , the value $n=1,2,3, \dots, W$ represents the order of the "combined" Fourier component being evaluated, C_n is a coefficient establishing the relative amplitude of the nth component and R is a number specifying the period

of the waveshape. The resultant musical sounds will have an ensemble effect characterized by the presence of beats between two notes separated in frequency by the amount

$$\Delta f = \frac{qR}{-\kappa} \quad (Eq. 2)$$

where κ is a positive or negative constant.

The resultant musical notes produced by the computer organ will have a harmonic spectrum typified by that of FIG. 1. Therein the solid lines represent the Fourier components $F_{true}^{(n)}$ at the nominally correct pitch. The broken lines designate the Fourier components $F_{offset}^{(n)}$ of the "out-of-tune" note, these being offset in frequency by an amount nqR/κ from the corresponding true-pitch component but equal in amplitude thereto. The amplitude of the waveshape constituted by the two sets of components of FIG. 1 is represented by:

$$X_o(qR) = \sum_{n=1}^W F_{true}^{(n)} + \sum_{n=1}^W F_{offset}^{(n)} \quad (Eq. 3)$$

$$= \sum_{n=1}^W C_n \sin \frac{\pi}{W} nqR + \sum_{n=1}^W C_n \sin \frac{\pi}{W} (nqR + \frac{nqR}{\kappa})$$

which is the equivalent of Equation 1.

Equation 1 readily is implemented in a computer organ since only one multiplication by C_n is required to evaluate each "combined" Fourier component, and only a single summation is needed to establish each sample point amplitude $X_o(qR)$. The waveshape amplitude contributions of the true and offset components are not separately evaluated and summed, as would be the case if Equation 3 were implemented. Accordingly, rather than requiring complete duplication of substantially the entire computer organ, including duplicate harmonic amplitude multipliers and accumulators, ensemble is obtained by the provision of straightforward circuitry for obtaining another sin value.

In the system disclosed herein, each "combined" Fourier component

$$F_{combined}^{(n)} = C_n \left[\sin \frac{\pi}{W} nqR + \sin \frac{\pi}{W} (nqR + \frac{nqR}{\kappa}) \right] \quad (Eq. 4)$$

is calculated by dividing the quantity nqR by the constant κ , adding nqR to the quotient, and obtaining the value $\sin \pi/W(nqR + (nqR/\kappa))$ from a memory table of sinusoid values. Concurrently the value $\sin(\pi/W)nqR$ is separately evaluated. The two sin values are added together, and the sum is multiplied by the associated harmonic coefficient C_n . The resultant combined Fourier component amplitudes are summed in an accumulator to obtain the waveshape sample point amplitude. The system may be replicated to obtain trio or quartet ensemble.

Advantageously the constant $\kappa = 2^m$ where m is an integer. Accordingly, in a binary implementation, division may be accomplished by right-shifting the quantity nqR (or alternatively, qR) in a shift register. The

amount of frequency offset Δf is a matter of design choice, but typically is between about 6 and 12 cents, where a cent is one-hundredth of a semitone (i.e., there are 1,200 cents per octave). This constant-cents offset provides a greater deviation for high-pitched notes and a lesser deviation for low notes, resulting in a pleasing ensemble effect.

BRIEF DESCRIPTION OF THE DRAWINGS

A detailed description of the invention will be made with reference to the accompanying drawings, wherein like numerals designate comprising parts in the several figures.

FIG. 1 is a harmonic spectrum typical of an ensemble effect.

FIG. 2 is an electrical block diagram of a computor organ configured to produce an ensemble effect.

FIG. 3 is an electrical block diagram of an alternative implementation of ensemble in a computor organ.

DESCRIPTION OF THE PREFERRED EMBODIMENTS

The following detailed description is of the best presently contemplated modes of carrying out the invention. This description is not to be taken in a limiting sense, but is made merely for the purpose of illustrating the general principles of the invention since the scope of the invention best is defined by the appended claims.

Structural and operational characteristics attributed to forms of the invention first described also shall be attributed to forms later described, unless such characteristics obviously are inapplicable or unless specific exception is made.

The computor organ 10 of FIG. 2 produces via a sound system 11 musical notes having an ensemble quality. For each note selected by the keyboard switches 12, the instrument 10 computes the amplitudes at successive sample points of a waveshape characteristic of ensemble. The computations are performed in accordance with Equation 1. The combined Fourier components are summed algebraically in an accumulator 13 which, at the end of each computation time interval t_x , contains the amplitude at the current sample point. This amplitude is provided via a gate 14, enabled by the t_x signal on a line 15, to a digital-to-analog converter 16 which supplies to the sound system 11 a voltage corresponding to the waveshape amplitude just computed. Computation of the amplitude at the next sample point subsequently is initiated, so that the analog voltage supplied from the converter 16 comprises a musical waveshape generated in real time and having ensemble characteristics. The period of the computed waveshape, and hence the fundamental frequency of the generated note, is established by a frequency number R selected by the keyboard switches 12. A set of such frequency numbers corresponding to the notes of the instrument is stored in a frequency number memory 17. At the end of each computation interval t_x , the frequency number R associated with a selected note is supplied via a gate 18 and added to the previous contents of a note interval adder 19. Thus the contents of the adder 19, supplied via a line 20, represents the value (qR) designating the waveshape sample point currently being evaluated. Preferably the note interval adder 19 is of modulo $2W$, where W is the highest order Fourier component evaluated by the system 10. Satisfactory pipe organ synthesis is achieved when

$W=16$ combined Fourier components are evaluated by the system 10.

System timing is established by a clock 22 and a counter 23 of modulo 16. During each waveshape amplitude computation interval t_x the clock 22 provides 16 timing pulses t_{cp} to the counter 23. The counter 23 in turn provides consecutive timing pulses t_{cp1} through t_{cp16} which enable calculation of the corresponding 16 combined Fourier components. The t_x signal on the line 15 is derived from the t_{cp16} signal slightly delayed in a delay unit 24.

Each of the calculation timing pulses t_{cp1} through t_{cp16} is supplied via an OR gate 25 to a gate 26. This gate 26 provides the value qR to a harmonic interval adder 27 which is cleared at the end of each amplitude computation interval t_x . Thus the contents of the harmonic interval adder 27 is incremented by the value (qR) at each calculation interval t_{cp1} through t_{cp16} , so that the contents of the adder 27 represent the quantity (nqR) . This value is available on a line 28.

An address decoder 30 accesses from a sinusoid table 31 the value $\sin(\pi/W)nqR$ corresponding to the argument nqR received via the line 28. The sinusoid table 31 may comprise a read only memory storing values of $\sin(\pi/W)\phi$ for $0 \leq \phi \leq W/2$ at intervals of D , where D is called the resolution constant of the memory. With this arrangement, the value $\sin(\pi/W)qR$ will be supplied on a line 31' from the sinusoid table 31 during the first calculation interval t_{cp1} . During the next interval t_{cp2} , the value $\sin(\pi/W)2qR$ will be present on the line 31'. Thus in general, the value $\sin(\pi/W)nqR$ will be provided from the sinusoid table 31 for the particular n^{th} order component specified by the timing interval output from the counter 23.

Concurrently, the value $\sin(\pi/W)(nqR+(nqR/\kappa))$ is evaluated in the following manner. The quantity (nqR) present on the line 28 and supplied via a switch 29 and a contact 29a is divided by the constant κ in a divider circuit 32. The quotient is summed with the value (nqR) in an adder 33 to provide on a line 34 the argument $(nqR+(nqR/\kappa))$. A separate memory address decoder 35 and sinusoid table 36 (similar to the decoder 30 and the table 31) are used to supply on a line 37 the value $\sin(\pi/W)(nqR+(nqR/\kappa))$ corresponding to the argument provided on the line 34.

The sin values present on the line 31' and 37 are summed in an adder 38 and the sum is supplied via a line 39 to a harmonic amplitude multiplier 40. There, the sum of the sin values is multiplied by the appropriate coefficient C_n supplied from a harmonic coefficient memory 41. The product, supplied via a line 42 to the accumulator 13, corresponds to the combined Fourier component $F_{\text{combined}}^{(n)}$ of the order n currently being evaluated. Thus within each amplitude computation interval t_x , the 16 combined Fourier components of order $n=1$ through $n=W-16$ will be provided to the accumulator 13 during the corresponding consecutive calculation time intervals t_{cp1} through t_{cp16} . At the end of the interval t_x , the accumulator 13 thus will contain the waveshape sample point amplitude $x_o(qR)$ for the sample point currently being evaluated. As described earlier, the sample point amplitudes obtained in the accumulator 13 are converted to an analog signal by the converter 16 and reproduced by the sound system 11 to provide musical notes having an ensemble effect.

As discussed above, in connection with Equation 2 and FIG. 1, the frequency separation between the true

pitch and "out-of-tune" notes is established by the constant. The value is a design choice, but in a binary system the constant advantageously is an integral power of 2. For example, a pleasing ensemble effect is achieved when the constant $\kappa=2^8=256$. This results in a frequency offset ΔF of about 7 cents. Pleasing ensemble also is achieved when $\kappa=2^7=128$, which provides a frequency offset ΔF of about 13 cents. A "rinky-tink" effect is achieved when $\kappa=2^6=64$, yielding a frequency offset of about 26 cents.

In a binary implementation in which $\kappa=2^m$, the divider 32 may comprise a shift register which right-shifts the quantity nqR by m digits. Since a right shift of one bit position is equivalent to division by 2, a shift of m positions is equivalent to division by 2^m . Commercially available integrated circuit, parallel-in, parallel-out shift registers such as the Texas Instrument Co. type 7495 may be employed as the divider 32.

The invention is not limited to binary systems, thus the value need not be a power of 2, and need not be a binary or decimal integer. The constant κ may be positive or negative. In the latter instance, the "out-of-tune" Fourier components will be lower in frequency (i.e., flat) with respect to the true pitch components. The value κ may be preset into the divider 32, or alternatively may be selected by the musician to adjust the ensemble frequency offset to a desired value.

The constant κ need not be the same value for all notes produced by the instrument 10. Alternatively, different values of κ may be used for each note or sets of notes. For example, individual values of κ may be stored in a memory 43 which is accessed in response to keyboard note selection when a switch 43' is closed. Thus when any keyboard switch 12 is depressed, the value κ corresponding to the selected note is accessed from the memory 43 and provided to the divider 32 for utilization during ensemble production. In such embodiment the memory 43 may be implemented using an integrated circuit programmable read only memory such as the Signetics SIG 8223 or the Texas Instruments type SN5488A. As another alternative, the value may be time variant. For example, a low frequency oscillator 44 connected to the divider 32 via a switch 44' may be used to vary the value at a periodic or non-periodic rate, resulting in a concomitant time-varying ensemble frequency offset.

The harmonic coefficient memory 41 advantageously comprises a read only memory containing values C_n appropriate to produce a note of desired tonal quality. For example, table I below sets forth typical harmonic coefficient values for obtaining a diapason tone. The value C_n corresponding to the nth Fourier component currently being evaluated is accessed from the memory 41 by a memory address control unit 45 which receives the calculation interval timing pulses t_{cp1} through t_{cp16} from the counter 23. Thus, e.g., when the timing pulse t_{cp1} is received, the control unit 45 causes the harmonic coefficient C_1 to be accessed from the memory 41 and supplied to the multiplier 40.

TABLE I

The harmonic coefficient memory 41 and address control 45 together may be implemented using a single integrated circuit read only memory such as the Signetics type 8223. Such a unit accepts a binary coded addressing signal. Correspondingly, the counter 23 may comprise a Signetics type 8281 16-state binary counter, the binary output of which may be supplied directly to the address control input of the type 8223 memory. A 20 Signetics type 8250 binary-to-octal decoder may be used in conjunction with the type 8281 counter to provide the separate t_{cp1} through t_{cp16} signal lines shown in FIG. 2. The type 8223 memory may be programmed to store the harmonic coefficients listed in table I above, 25 or other values of C_n appropriate to produce other tones.

The frequency number memory 17 likewise may be implemented using a conventional integrated circuit read only memory such as the Signetics type 8223. The 30 following table II shows typical values for the frequency number R for the notes between C_3 and C_5 .

The note interval adder 19, the harmonic interval adder 27 and the accumulator 13 may be implemented 55 using conventional integrated circuit full adders such as the Signetics type 8268 or the Texas Instrument Co. type SN5483 or SN7483. These may be connected as shown in the section entitled "Accumulators" of the textbook "Computer Logic" by Ivan Flores, Prentice-Hall, 1960, to accumulate the sum. Each sinusoid table 31, 36 and memory address decoder 30, 35 may comprise a conventional integrated circuit read only memory, such as the Texas Instrument Co. type TMS4400 programmed to store sin values. A useful integrated circuit having prestored sinusoid table and addressing circuitry also is available from the Texas Instrument Co. as a type TMS4405 device. A single sinusoid table could be time-shared in place of separate tables 31 and 36. The harmonic amplitude multiplier 40 may be im-

plemented as shown in the application sheet on page 28 of the Signetics catalog entitled "Digital 8000 Series TTL/MSI," copyright 1971, using Signetics SIG 8202 buffer registers and 8260 arithmetic element. The multiplier 40 also could be implemented using a Signetics 8243 scaler.

A "trio" ensemble effect can be achieved by the computer organ 10 using the optional circuitry shown in FIG. 2 and actuated when the switch 29 is set to engage the contact 29b. Trio ensemble is produced in a pipe organ by simultaneously sounding three pipes which are frequency offset with respect to each other. The effect is synthesized in the instrument 10 by implementing the following equation:

$$\begin{aligned}
 x_o(qR) &= \sum_{n=1}^W F_{\text{true}}^{(n)} + \sum_{n=1}^W F_{\text{offset}}^{(n)} + \sum_{n=1}^W F_{\text{offset}}^{(n)} \\
 &= \sum_{n=1}^W C_n \sin \frac{\pi}{W} nqR + \sum_{n=1}^W C_n \sin \frac{\pi}{W} (nqR + \frac{nqR}{\kappa}) + \sum_{n=1}^W C_n \sin \frac{\pi}{W} (nqR + \frac{nqR}{\kappa'}) \\
 &= \sum_{n=1}^W C_n [\sin \frac{\pi}{W} nqR + \sin \frac{\pi}{W} (nqR + \frac{nqR}{\kappa}) + \sin \frac{\pi}{W} (nqR + \frac{nqR}{\kappa'})] \quad (\text{Eq. 5})
 \end{aligned}$$

wherein $F^{(n)}_{\text{offset}}$ represents the Fourier components associated with a third tone. These components are offset in frequency by an amount nqR/κ' from the corresponding true-pitch components.

Comparison of Equation 5 shows that it is the same as Equation 1 except for addition of the third sin term. This value $\sin(\pi/W)(nqR + (nqR/\kappa'))$ is evaluated by the components designated 46 through 49 in FIG. 2. Specifically, the value (nqR) from the line 28 is divided by the constant κ' in a divider circuit 46 which may be implemented in the same manner as the divider 32. The quotient is summed with the value (nqR) by an adder 47. A memory address decoder 48 and a sinusoid table 49 (similar to the decoder 30 and sinusoid table 31) are used to obtain the value $\sin(\pi/W)(nqR + (nqR/\kappa'))$ for the argument provided by the adder 47. This sin value is supplied via the line 50 to the adder 38 where it is summed with the other sin terms, present on the lines 32 and 37, associated with the true-pitch and first offset components of corresponding order. The sum of the three sin values then is multiplied by the coefficient C_n in the multiplier 40 and added to the previous contents of the accumulator 13. At the end of each computation interval t_x , the accumulator 13 will contain the waveshape amplitude for the current sample point, evaluated in accordance with equation 5. As successive sample point amplitudes are obtained in the accumulator 13, they are converted to analog form and reproduced by the sound system 11 to produce musical notes having a "trio" ensemble effect.

In the alternative embodiment of FIG. 3, the computer organ 10A also produces ensemble sounds in accordance with equation 1. In this implementation, the value (qR) on the line 20 is divided by the constant in a divider 53. The quotient is summed with the value (qR) in an adder 54 to obtain the sum $(qR + (qR/\kappa))$. At each calculation interval t_{cp1} through t_{cp16} this sum is provided via a gate 55 to a harmonic interval adder 56 like the adder 27. The harmonic interval adder 56 is cleared at the end of each computation interval t_x , so

that the contents of the adder 56 represents the quantity $n(qR/\kappa)$ for the nth order component currently being evaluated. This value is supplied via a line 57 to a memory address decoder 58 and a sinusoid table 59 identical in function and operation to the decoder 35 and sinusoid table 36 of FIG. 2. The obtained value $\sin(\pi/W)n(qR + (qR/\kappa))$ is supplied via a line 60 to the adder 38 where it is summed with the value $\sin(\pi/W)nqR$ present on the line 32. The sum is supplied via the line 39 to the harmonic amplitude multiplier 40 (FIG. 2). The remaining circuitry of the instrument 10A is identical to that of FIG. 2, and operates correspondingly to provide musical sounds having an ensemble quality.

Intending to claim all novel, useful and obvious fea-

tures shown or described, the applicant claims:

1. In an electronic musical instrument wherein the amplitudes of a waveshape are computed at regular time intervals t_x from stored harmonic coefficients, musical notes being produced from said computed amplitudes as said computations are carried out in real time, the improvement for producing an ensemble effect comprising:

first means for evaluating a set of "combined" Fourier components during subintervals within each time interval t_x , each combined Fourier component being the sum of a first constituent Fourier component at the nominal true-pitch of the selected note and a second constituent Fourier component offset in frequency from the corresponding true-pitch first constituent Fourier component, the first and second constituent Fourier components of corresponding order having an equal amplitude established by said stored harmonic components, an accumulator, connected to receive said combined Fourier components from said first means, for accumulating all the the combined Fourier components evaluated during each interval t_x to obtain a waveshape amplitude for a certain sample point, sample point means operative at the end of each interval t_x for incrementing the effective sample point (qR) for which said resultant waveshape amplitude is established and for supplying the effective sample point (qR) value to said first means, and

means, connected to receive said waveshape amplitudes from said accumulator, for converting said resultant waveshape amplitudes to sounds, said converting being carried out, in real time as said waveshape amplitudes are computed, the sounds so produced exhibiting an ensemble effect.

2. A musical instrument according to claim 1 wherein said sample point means establishes a sample point value qR , where q is an integer incremented each inter-

val t_r and R is a constant frequency number establishing the nominal fundamental frequency of the produced note, and wherein said first means comprises;

trigonometric function circuitry, utilizing the sample point value qR , for evaluating a pair of like trigonometric functions the arguments of which correspond respectively to the sample point nqR of the true pitch first constituent Fourier component and to the sample point $(nqR+(nqR/\kappa))$ of the second constituent Fourier component, where n designates the order of each combined Fourier component, and κ is a constant establishing the extent of frequency offset of said second constituent Fourier component,

an adder, receiving the evaluated trigonometric function from said circuitry, for summing said pair of trigonometric functions for each order n , and a multiplier connected to said adder and receiving said stored harmonic components, for multiplying each trigonometric function sum from said adder by the harmonic coefficient for the corresponding order n , the product being the combined Fourier component value which is supplied to said accumulator.

3. As an electronic musical instrument exhibiting an ensemble effect:

first means for computing at regular time intervals t_r the amplitudes $X_o(qR)$ of a waveshape, where q is an integer incremented each time interval t_r , in accordance with the relationship

$$X_o(qR) = \sum_{n=1}^W C_n [\sin_{W}^{nqR} + \sin_{W}^{(nqR+\frac{nqR}{\kappa})}]$$

wherein $n=1,2,3, \dots, W$ designates the order of the Fourier components included in each waveshape amplitude computation, wherein C_n is a coefficient establishing the relative amplitude of the corresponding n^{th} component, wherein R is a number specifying the period of said waveshape, and wherein κ is a constant establishing the ensemble frequency offset, and

second means responsive to said first means for providing ensemble tones from said computed amplitudes, and wherein said first means comprises;

a coefficient memory storing said harmonic coefficients C_n ,

at least one sinusoid table comprising a memory storing values of $\sin(\pi/W) \phi$ for $0 \leq \phi \leq W/2$ at intervals of D where D is a resolution constant,

a frequency number memory containing values of R associated with selectable musical notes and note selection circuitry for accessing from said frequency number memory the value R for each selected note,

first sinusoid evaluation circuitry connected to one of said sinusoid tables to calculate $\sin(\pi/W)nqR$ for each value $n=1,2,3, \dots, W$ in accordance with the selected value R , all of said calculations being performed within each interval t_r ,

second sinusoid evaluation circuitry connected to a sinusoid table to calculate $\sin(\pi/W)(nqR+(nqR/\kappa))$ for each value $n=1,2,3, \dots, W$ in accordance with the selected value R and said constant κ , all of said calculations being performed within each interval t_r ,

a first adder, said first and second evaluation circuitry concurrently providing to said adder the re-

spective values $\sin(\pi/W)nqR$ and $\sin(\pi/W)(nqR+(nqR/\kappa))$ for the same order n , said respective sin values being summed by said adder, a harmonic amplitude multiplier connected to receive from said coefficient memory the harmonic coefficient C_n corresponding to said same order n of the sin values summed by said adder, and operative to multiply the sin value sum from said adder by said received coefficient C_n , and an accumulator for algebraically summing, during each interval t_r , the products from said multiplier for all values $n=1,2,3, \dots, W$ to obtain each waveshape amplitude $X_o(qR)$.

4. A musical instrument according to claim 3 having first and second like sinusoid tables, said first and second evaluation circuitry respectively utilizing said first and second sinusoid tables.

5. A musical instrument according to claim 3 wherein said first means further comprises;

a note interval accumulating adder of modulo $2W$, and first gate circuitry connected to said frequency number memory and to said note interval adder for supplying to said note interval adder at each interval t_r the value R accessed from said frequency number memory, so that the contents of said note interval adder represents the quantity (qR) , and wherein said first and second evaluation circuitry are connected to receive said quantity (qR) from said note interval adder.

6. A musical instrument according to claim 5 wherein said first evaluation circuitry comprises;

a first harmonic interval accumulating adder cleared at the end of each interval t_r , second gate circuitry for supplying to said first harmonic interval adder the quantity (qR) from said note interval adder during successive subintervals of each interval t_r , so that the contents of said first harmonic interval adder successively represent the quantity (nqR) for different values of n , and first circuitry utilizing one of said sinusoid tables to obtain the values $\sin(\pi/W)nqR$ for each argument (nqR) supplied from said first harmonic interval adder.

7. A musical instrument according to claim 6 wherein said second evaluation circuitry comprises;

a divider connected to receive the contents (nqR) of said first harmonic interval adder and to divide said value (nqR) by said constant κ ,

a second adder for summing the outputs of said divider and said first harmonic interval adder to obtain the arguments $(nqR+(nqR/\kappa))$, and second circuitry utilizing one of said sinusoid tables to obtain the values $\sin(\pi/W)(nqR+(nqR/\kappa))$ for each argument supplied from said adder.

8. A musical instrument according to claim 7 for providing trio ensemble, further comprising;

a second divider connected to receive the contents (nqR) of said first harmonic interval adder and to divide said value (nqR) by a constant κ' different from κ ,

another adder for summing the outputs of said second divider and said first harmonic interval adder to obtain the argument $(nqR+(nqR/\kappa'))$, and third circuitry utilizing one of said sinusoid tables to obtain the values $\sin(\pi/W)(nqR+(nqR/\kappa'))$ for each argument supplied from said other adder, and

11

wherein said first adder sums the three sin values provided by first, second and third utilizing circuitry.

9. A musical instrument according to claim 7 wherein said value $\kappa=2^m$ where m is an integer, and wherein said divider comprises a binary shift register which accepts said value (nqR) in binary and to right shift said value by m binary positions to perform said division by κ .

10. A musical instrument according to claim 6 wherein said second evaluation circuitry comprises;

a divider connected to receive the contents (qR) of said note interval adder and to divide said value (qR) by said constant κ ,

an adder for summing the outputs of said divider and said note interval adder to obtain the value $(qR+qR/\kappa)$.

a second harmonic interval adder cleared at the end of each interval t_x ,

second gating circuitry for providing said obtained value $(qR+(qR/\kappa))$ to said second harmonic inter-

12

val adder during successive subintervals of said interval t_x so that the contents of said second harmonic interval adder successively represent the arguments $n(qR+(qR/\kappa))$ for different values of n , and

second circuitry utilizing a sinusoid table to obtain the values $\sin(\pi/W)n(qR/\kappa))$ for each argument supplied from said second harmonic interval adder.

11. A musical instrument according to claim 3 further comprising means for providing a selectable value of κ to said second sinusoid evaluation circuitry.

12. A musical instrument according to claim 11 wherein said means for providing comprises a frequency offset memory storing different values of κ associated with different notes, said note selection circuitry also causing the value of κ associated with each selected note to be accessed from said frequency offset memory and supplied to said second sinusoid evaluation circuitry.
